UNITED STATES PATENT OFFICE.

JULIUS M. REIS, OF NEW YORK, N. Y.

EMBROIDERY.

1,314,213.

Specification of Letters Patent. Patented Aug. 26, 1919.

Application filed March 30, 1917. Serial No. 158,536.

To all whom it may concern:

Be it known that I, JULIUS M. REIS, a citizen of the United States, and a resident of the city, county, and State of New York, 5 have invented certain new and useful Improvements in Embroidery, of which the following is a specification.

My invention relates to embroidery, and more particularly to a new method of making 10 embroidered articles and to an article of dry goods having an embroidery filler form thereon adapted to be covered by hand-embroidery threads.

The object of the invention is to provide 15 an article of dry goods for commerce, of the character that it is usually desired to embroider, having formed directly thereon as a component part thereof a filler form for the embroidery that is substantially as uniform 20 and as accurate to outline as are the well-known stamped-out types of filler forms, and that is substantially as flexible and durable as the cloth article itself, and which is to be embroidered over by hand.

25 The object and advantages of the invention will more fully appear from the following description taken in connection with the accompanying drawings, in which—

Figure 1 shows a plan view of a portion 30 of an article of dry goods, for example the corner of a face towel, embodying my invention; and

Fig. 2 is a sectional view on line 2--2 of Fig. 1.

35 Fig. 3 is a similar section longitudinally of the filler embroidery threads and illustrating diagrammatically the relatively long stitches on the top or upper face of the article and the relatively short stitches on 40 the bottom face thereof, and also the transverse hand embroidery stitches.

Referring to the drawings, 1 represents 45 the corner or fragment of any article of commerce that it may be desired to embroider on, as for example a face towel, and 2 represents the filler form built up or formed thereon by stitches and serving the double purpose of outlining the desired design and as a foundation or filler for the 50 hand-embroidery threads to be placed thereon. It is necessary that the form be mechanically built up by stitches on the article by some suitable machine by means of which the placing of the stitches on the cloth is 55 guided or controlled by some suitable design blank, plate or equivalent device which might

be termed a master design, because without this the outline of the design cannot be precisely formed by stitches on the cloth articles so as to give the accurate line necessary for 60 the purpose intended. With a machine using a master design, the stitches 3 are formed directly on the article so as to form a component part thereof. The stitches on top of the article are made relatively long and 65 those beneath relatively short so as to get the desired depth of padding on top and as little padding as possible beneath the cloth article.

Fig. 2 is a cross-sectional view showing 70 the depth of the padding above the cloth due to the long stitches.

As illustrated in Fig. 3 the machine embroidered stitches which run longitudinally of the elements of the embroidery design, 75 are relatively long on the top of the article and relatively short on the bottom face of the article as indicated at 3. In this figure the hand embroidery stitches passing transversely over and substantially covering the 80 machine embroidery stitches are indicated at 4.

It will be noted that the machine embroidered filler stitches of any part of the design run longitudinally of that part, the object 85 being to have the stitches making up the filler form lie in some direction other than directly transverse or at right angles to the length of the particular part of the design where the stitches are located, so that the 90 transverse hand-embroidery threads which run at right angles to the length of any particular part of the design will be supported by the relatively longitudinally arranged threads below, rather than by threads paralleling the hand-embroidery threads; because if the supporting or filler form threads were arranged parallel to the hand-embroidery threads, the latter would in some instances, according to the tension placed 100 thereon in embroidering, be drawn down between two adjacent filler form threads, or in laundering the filler form threads may work up between the hand-embroidery threads, thus in either event causing a rough 105 and irregular surface on the hand-embroidery.

Articles of dry goods having embroidery filler forms formed thereon in this manner are much more desirable than where the 110 filler forms are merely of the usual form to be pasted or basted thereon, because the

form is not only held with absolute certainty in the right location, and of the desired clearness and accuracy of outline, but it is substantially as flexible and durable 5 as the cloth itself, and is free from any pulp substances that might wash through the embroidery threads; and because filler forms that are not built up as by stitches directly on the cloth article are liable to become dis- 10 placed in some manner, thus roughening or rupturing the delicate hand-embroidery threads. Furthermore, the filler form, when made of stitches of thread, has the desired capacity for moisture-absorption and it 15 dries out with the desired rapidity. Where felt forms, for example, have been used, in some instances it has been found that, due to their density and their moisture-absorbing capacity, they do not dry out with sufficient rapidity to make them desirable for 20 all classes of embroidery.

It will thus be seen that my invention provides an article of commerce, to wit, an article of dry goods having an embroidery 25 filler form of the same general nature and characteristics as to pliability, moisture-absorbing capacity and durability as the fabric on which it is worked, formed directly on the fabric as a component part 30 thereof, and serving as an accurate outline of the design, all ready to be covered by hand-embroidery threads.

Having thus described my invention, what I claim as new and desire to secure by Letters Patent, is:—

1. A cloth article of commerce adapted 40 to be hand embroidered, having machine embroidery on its upper surface to serve as a pattern for hand embroidery in the desired design and forming a component part of the cloth article, said embroidered pattern having relatively long stitches on the upper surface of the cloth article and relatively short stitches on the lower surface thereof, 45 and with the upper relatively long stitches running longitudinally of the design elements, whereby the machine embroidery threads serve both as a pattern for hand em-

broidery thereof and as a filler for the hand embroidery.

2. The improved method of making hand embroidered cloth articles which consists in machine embroidering the desired design from a master pattern directly on the cloth article, with relatively long stitches on its 55 upper face and relatively short stitches on its lower face and with upper stitches running longitudinally of the design elements, and then hand embroidering over said design on and through the cloth article, with 60 the threads passing transversely of said longitudinal machine embroidery threads to substantially cover the machine embroidery threads on the top of the article, whereby the machine embroidery serves both as a design 65 for the guidance of the operator and as a filler for the hand embroidery.

3. The improved method of making hand embroidered cloth articles which consists in machine embroidering the desired design 70 from a master pattern directly on the cloth article, with upper stitches running longitudinally of the design elements, and then hand embroidering over said design on the cloth article, with threads passing transversely of said longitudinal machine embroidery threads to cover the machine embroidery threads on the top of the article, whereby the machine embroidery serves both 75 as design for the guidance of the operator 80 and as a filler for the hand embroidery.

4. The improved method of making hand embroidered cloth articles which consists in machine embroidering the desired design from a master pattern directly on the cloth 85 article and then hand embroidering over said design on the cloth article, to cover the machine embroidery threads on the top of the article, whereby the machine embroidery serves both as design for the guidance 90 of the operator and as a filler for the hand embroidery.

In testimony whereof, I have signed my name to this specification.

JULIUS M. REIS.
